UNITED STATES PATENT OFFICE.

ARTHUR SCHILLING, OF ROCHESTER, NEW YORK, ASSIGNOR TO AMERICAN POULTRY
ASSOCIATION, OF MANSFIELD, OHIO.

DESIGN FOR AN EMBLEM.

42,926.

Specification for Design.

Patented Aug. 20, 1912.

Application filed May 17, 1912. Serial No. 698,045. Term of patent 14 years.

To all whom it may concern:

Be it known that I, ARTHUR SCHILLING, a citizen of the United States, and residing at Rochester, in the county of Monroe and State of New York, have invented a new, original, and ornamental Design for an Emblem, of which the following is a specification, reference being had to the accompanying drawing, forming a part thereof, in which the figure is a plan view of an emblem or insignia, showing my design.

I claim:

The ornamental design for an emblem, as shown.

ARTHUR SCHILLING.

Witnesses:

J. H. DRENENSTEDT,
Wm. C. DENNY.
